UNITED STATES PATENT OFFICE.

JULIUS KELLER, OF PHILADELPHIA, PENNSYLVANIA, ASSIGNOR, BY MESNE ASSIGNMENTS,
TO CHICAGO PNEUMATIC TOOL COMPANY, A CORPORATION OF NEW JERSEY.

PNEUMATIC RIVETER.

No. 878,805.

Specification of Letters Patent.

Patented Feb. 11, 1908.

Application filed December 11, 1900. Serial No. 39,570.

To all whom it may concern:

Be it known that I, JULIUS KELLER, a citizen of the United States, residing in the city and county of Philadelphia, State of Pennsylvania, have invented a new and useful Improvement in Pneumatic Riveters, and it consists of novel details of construction, all as will be hereinafter fully set forth, and particularly pointed out in the claims.

Figure 1 represents a longitudinal sectional view of a pneumatic riveter embodying my invention, certain of the parts being shown in elevation and the riveter being shown in connection with a yoke to which the same is applicable. Fig. 2 represents a longitudinal vertical section of the riveter seen in Fig. 1, on an enlarged scale, the section being taken on a different axial line, showing more especially the stop valve, stop valve rod and their adjuncts. Fig. 3 represents a section on line *x—x* Fig. 2. Fig. 4 represents a section on line *y—y* Fig. 2. Figs. 5 to 8 represent details.

Similar letters of reference indicate corresponding parts in the figures.

Referring to the drawings: 1 designates a casing connected to the yoke 2 by the clamping piece 3, and held in position by means of the screw bolts 4, and the clamp screw 5, although it is evident that other equivalent fastenings may be employed.

6 designates an outside tool cylinder within the casing 1, and 7 designates the inside tool cylinder which is forced or otherwise inserted into said first-mentioned cylinder, said inside tool cylinder having the hammer or piston 8 adapted to reciprocate therein.

9 designates the valve box, within which reciprocates the distributing valve 10 provided with differential pressure areas, said valve box having the valve top 11, said valve box, valve and top being similar in construction, location and operation to the structure protected in Letters Patent No. 647,415, granted to me April 10th, 1900, in the same class of invention and as the operation will be apparent to those skilled in this art, I have deemed a detailed description thereof unnecessary.

12 designates a clamping device adapted to hold the valve mechanism tightly against the tool cylinder, although it will be apparent that other suitable means may be employed if desired said clamping device being pre-

vented from unscrewing by means of the 55 jam nut 13.

14 designates a cupped shaped washer of leather or other suitable material, which is held in position against the clamping device by the washer 15 or other suitable means, it 60 being evident that the above parts are contained within the cylinder head 16, which closes up the backside or rear end of the cylinder.

17 designates a throttle valve, having the 65 operating lever 18, whereby the admission of the motive fluid to the riveter is controlled.

19 designates a ring or annulus, which is located between the casing 1 and the outer 70 tool cylinder 6, said ring being adapted to form a shoulder and being held in position by means of the bolts 20 or other suitable fastening devices.

21 designates the button set bushing, 75 which is screwed or otherwise secured in the nose end of the outer tool cylinder 6, it being noted that the movable stop valve washer 22, is located between the inner end of the bushing 21 and the shoulder 23 of the inner 80 cylinder 7.

24 designates the button set, which has the recess 25 therein, which co-acts with the button set clamp 26, whereby said button set is held to said button set bushing, it being seen that said button set has the shank 85 or extension 27, which is freely movable and adapted to contact with the washer 22, as will be hereafter explained.

28 designates the holder-on which is fastened to the yoke 2 by the clamping screw 29, or other suitable means, said holder-on having a button set 30 mounted therein.

31 designates a stop valve, which is located in a suitable recess 32 in the valve box 95 9, said stop valve consisting of the heads 33 connected by the neck 34, one of said heads being provided with the stem 35, which is adapted to contact with the longitudinally-extending stop valve rod 36, which is best 100 seen in Figs. 2 and 5, said stop valve being held in its forward position by means of fluid pressure through the port 37, although it is evident that a spring or other analogous means may be employed for this purpose if 105 desired. The throttle lever 18 is shown in Fig. 1 as standing in its middle or upright position, and the air or fluid pressure enter-

ing the port 38, passes through the groove 39 of the valve and enters the wall of the casing through the port 40, and passes through the passage 41, into the casin at the port 42, whereupon pressure is exerted upon the shoulder 43. In this position, the pressure chamber 44 is connected with the exhaust through ports 45, 46 and 47, a communication being now had with the 10 main exhaust port 48 in the throttle valve, and it will be apparent that the pressure exerted against the shoulder 43, will force the tool outwardly or against the rivet 49.

In turning the throttle valve lever 18 to 15 the extreme left, as shown in Fig. 3, the inlet groove 50 of the throttle valve will be connected with the ports 51, and fluid pressure will pass through the ports 52, 53 and 54 into the casing 1, and the pressure being 20 admitted to the distributing valve through the passage 55, the hammer will operate in the usual manner as will be evident to those skilled in the art, it being also apparent that the pressure against the back end of the tool 25 as well as upon the shoulder 43, will force the tool to follow up the work until the rivet head is finished. In turning the throttle valve lever 18 back again to the position seen in Fig. 1, the inlet for the compressed 30 air or other motive fluid to the port 54 is closed and as no air enters the distributing valve, the piston or hammer 8 will stop working, but the tool will remain in the same position against the rivet head as the pressure 35 against the shoulder 43 is continuous.

Upon turning the throttle valve lever 18 to the extreme right as seen in dotted lines in Fig. 3, the port 56 will now be open for the admission of fluid pressure, which will enter 40 the pressure chamber 44, through the ports 45, 46 and 47, and as the pressure area 57 is greater than the pressure area afforded by the shoulder 43, it will be apparent that the whole tool comprising the outside or outer 45 tool cylinder 6 and its adjuncts will be forced backwardly until it contacts with the head 16, the parts being now in substantially the position seen in Fig. 1.

The distributing valve 10 which I employ 50 is constructed in substantially the same manner as the distributing valve seen in my prior patent above referred to although it will be apparent that in carrying out the broad idea of my invention, as far as it relates 55 to the principle of moving the tool proper or its cylinder towards and away from the work by fluid pressure without starting the operation of the hammer or piston, other forms of distributing valves may 60 be employed without departing from the spirit of my invention. As explained in my prior patent the valve 10 is provided with the flange or small pressure area 58 and also with the larger flange or large pressure 65 area 59, whereby the differential pressure

areas are obtained, and when the parts are in the position seen in Fig. 2, it will be apparent that the hammer or piston 8 has reached the extreme forward end of its stroke, thus opening the port 60, which connects with the 70 large pressure area of said valve through the ports 61, 62, 63, 64 and 65, the relative positions of these ports being best understood from the dotted lines in Fig. 2. The pressure which enters the piston chamber through 75 the ports 66^x and 67^x seen in full lines at the right of Figs. 1 and 2, would now be admitted to the large pressure area 59 of the valve 10 by the ports 60, 61, 62, 63, 64 and 65, above referred to, and said valve 10 will 80 be forced forwardly or to the left of the position seen in Fig. 5 and live fluid pressure would be conducted through the ports 66, 67 and 68 seen in full lines in Fig. 1 and in dotted lines in Fig. 2 to the front end of the 85 piston or hammer 8, whereby the latter will move from the position seen in Fig. 2 into the position seen in Fig. 1.

I desire to call especial attention to another novel feature of my invention whereby 90 provision is made for preventing reciprocation of the hammer 8, unless the button set 24 is pressed against the rivet, the detailed operation being as follows: I place the recess 32 of the valve box 9, the stop valve 31 whose function is to cut off the connection between 95 the ports 60 and 65, seen dotted in Fig. 2, and it will be apparent that when said stop valve is in the position seen in Figs. 2 and 7, the port 63 is closed and the pressure from 100 the piston chamber cannot go through the ports 64 and 65 to the large pressure area 59 of the distributing valve, until the button set 24 is pressed against the work, which will bring the washer 22, against the shoulder 23, 105 on the inner cylinder 7. The stop valve rod 36, by reason of the backward movement of the washer 22, will be moved to the right of the position seen in Fig. 2, whereupon the stop valve will be moved from the position 110 seen in Fig. 2, whereby the ports 62 and 63 are thrown into communication by reason of the connecting neck 34 of said stop valve, and pressure can freely pass through the 115 ports 60, 61, 62, 63, 64 and 65 to the large pressure area 59 of the differential distributing valve, which will now be forced forwardly into the position seen in Fig. 1, thereby opening the ports 66, 67 and 68 and the hammer 8 will be forced backwardly or to the right 120 of the position seen in Fig. 2, which operation can be continued at pleasure so long as the stop valve occupies the position seen in Fig. 6. At the same time that the distributing valve is forced forwardly or into the position 125 seen in Fig. 1 and the ports 66, 67 and 68 are open for the admission of live pressure into the front end of the cylinder, and the ports 66^x and 67^x will be open for the exhaust through the neck, which joins the differential 130

pressure areas 58 and 59 of the distributing valve 10, said exhaust passing through the ports 71 and 70 to the atmosphere through the port 72.

5 The operation of the tool will continue as long as the button set is pressed against the work and the stop valve held open or in the position seen in Fig. 6, but as soon as the button set is released from the rivet the air 10 pressure through the port 37, will force the stop valve, stop valve rod and washer forwardly into the position seen in Fig. 2, said washer being now in contact with the button set bushing and the hammer 8 will stop 15 working even if or while the pressure is admitted to the distributing valve 10.

It will be apparent that in carrying out the broad principle of my invention, the same will be applicable to other forms of pneumatic tools, which are used for other purposes than riveting, and I also desire it to be understood that any other suitable form of impact device other than the button set 24 may be employed without departing from 25 the spirit of my invention. Especial emphasis is also laid upon the feature of moving the tool proper by air pressure against the work and from the work according to requirements without starting the operation of 30 the hammer or piston, even although live fluid pressure is acting upon the distributing valve or said hammer. It will be obvious also that slight changes may be made in the form of the stop valve 31, whereby the desired result may be effected, and that other or equivalent means may be employed for actuating the stop valve forwardly or backwardly than that shown which will come within the scope of my invention, as for example, a spring may be employed in the place of the fluid pressure which enters the recess 32 through the port 37.

It will be apparent that further changes may be made by those skilled in the art 45 which will come within the scope of my invention, and I do not therefore desire to be limited in every instance to the exact construction herein shown and described.

It will be evident that the pneumatic tool 50 embodying the valve, hammer and co-acting ports in my present invention contains the same advantages which exist in the tool protected in my prior patent No. 647,415, herein above referred to, since before the hammer 55 strikes the impact device or shank 27 of the button set, the valve 10 will move in the same direction and when the blow of the hammer is delivered the valve is on the left hand side, the blow instead of rebounding the 60 valve from its seat tending to hold said valve more firmly seated; since the momentum or slight forward movement imparted to the tool when said blow is struck, must simultaneously impart a slight forward movement 65 to the valve since the latter and said hammer

move in same direction, and it will be apparent that since all the ports are open at the right time, the regular and uniform movement of the valve and also of the hammer being unobstructed will prevent jarring and other objectionable features of pneumatic tools now in use, as the same is reduced to a minimum.

In Figs. 5 to 8, I have shown sectional and perspective views of the throttle valve and its adjuncts employed, wherefrom it will be seen that the throttle valve is provided with a flattened side 78, through which communication is had with the longitudinally-extending main exhaust port 48, it being apparent 80 that the solid portions or heads 79 and 80 are connected by the neck 81, whereby the groove 39 is formed, said solid portion 78 being flattened on its surface opposite the flattened portion 78 as indicated at 82, wherefrom it will be seen that the operation as above described with respect to the throttle valve can be readily effected.

Having thus described my invention, what I claim as new, and desire to secure by Letters Patent, is:

1. In a pneumatic tool, the combination of the inner tool cylinder, the casing and the outer tool cylinder having a shoulder, of a piston movable in the inner cylinder, a hollow distributing valve, the interior surface of which is open to fluid pressure upon opening the throttle valve, said valve movable in the same direction as the piston but independently thereof, ports controlled by said valve, a pressure chamber at the rear of the inner tool cylinder, a throttle valve connected with said cylinder for controlling the admission of motive fluid, a passage controlled by said throttle valve through the 100 casing for the motive fluid to exert pressure against said shoulder, a removable end for said casing having a port therein controlled by said throttle valve, opening into the casing at the end, and a stop valve acting in conjunction with said distributing valve, exhaust ports in communication with said pressure chamber and controlled by the throttle valve, a pressure area in said pressure chamber greater than that of said shoulder, said stop valve movable parallel with the distributing valve and controlling ports common to both of said valves, and means whereby said stop valve is positively operated in one direction mechanically and 115 in the opposite direction by fluid pressure.

2. In a pneumatic tool, the combination of the inner tool cylinder, the casing, and the outer tool cylinder having a shoulder, of a piston movable in the inner cylinder, a hollow distributing valve, the interior surface of which is open to fluid pressure upon opening the throttle valve, said valve movable in the same direction as the piston but independently thereof, ports controlled by said 125 130

valve, a pressure chamber at the rear of the inner tool cylinder, a throttle valve parallel with said cylinder for controlling the admission of motive fluid, a passage controlled by 5 said throttle valve through the casing for the motive fluid to exert a pressure against said shoulder, and a stop valve acting in conjunction with said distributing valve, exhaust ports in communication with said pressure chamber and controlled by the throttle valve, a pressure area in said pressure chamber greater than that of said shoulder, said stop valve movable parallel with the distributing valve and controlling ports common to both of said valves, and means whereby said stop valve is positively operated in one direction mechanically and in the opposite direction by fluid pressure. 10

3. In a pneumatic tool, the combination of the inner tool cylinder, the casing, and the outer tool cylinder having a shoulder, of a piston movable in the inner cylinder, a hollow distributing valve the interior surface of which is open to fluid pressure upon opening 15 the throttle valve, said valve movable in the same direction as the piston but independently thereof, ports controlled by said valve, a pressure chamber at the rear of the inner tool cylinder, a throttle valve for controlling 20 the admission of motive fluid, a passage controlled by said throttle valve through the casing for the motive fluid to exert a pressure against said shoulder, and a stop valve acting in conjunction with said distributing valve, exhaust ports in communication with said pressure chamber and controlled by the throttle valve, a pressure area in said pressure chamber greater than that of said shoulder, said stop valve movable parallel with the distributing valve and controlling ports common to both of said valves, and means whereby said stop valve is positively operated in one direction mechanically and in the opposite direction by fluid pressure. 25

3. In a pneumatic tool, the combination of the inner tool cylinder, the casing, and the outer tool cylinder having a shoulder, of a piston movable in the inner cylinder, a hollow distributing valve the interior surface of which is open to fluid pressure upon opening the throttle valve, said valve movable in the same direction as the piston but independently thereof, ports controlled by said valve, a pressure chamber at the rear of the inner tool cylinder, a throttle valve for controlling 30 the admission of motive fluid, a passage controlled by said throttle valve through the casing for the motive fluid to exert a pressure against said shoulder, and a stop valve acting in conjunction with said distributing valve, exhaust ports in communication with said pressure chamber and controlled by the throttle valve, a pressure area in said pressure chamber greater than that of said shoulder, said stop valve movable parallel with the distributing valve and controlling ports common to both of said valves, and means whereby said stop valve is positively operated in one direction mechanically and in the opposite direction by fluid pressure. 35

3. In a pneumatic tool, the combination of the inner tool cylinder, the casing, and the outer tool cylinder having a shoulder, of a piston movable in the inner cylinder, a hollow distributing valve the interior surface of which is open to fluid pressure upon opening the throttle valve, said valve movable in the same direction as the piston but independently thereof, ports controlled by said valve, a pressure chamber at the rear of the inner tool cylinder, a throttle valve for controlling 40 the admission of motive fluid, a passage controlled by said throttle valve through the casing for the motive fluid to exert a pressure against said shoulder, and a stop valve acting in conjunction with said distributing valve, exhaust ports in communication with said pressure chamber and controlled by the throttle valve, a pressure area in said pressure chamber greater than that of said shoulder, said stop valve movable parallel with the distributing valve and controlling ports common to both of said valves, and means whereby said stop valve is positively operated in one direction mechanically and in the opposite direction by fluid pressure. 45

3. In a pneumatic tool, the combination of the inner tool cylinder, the casing, and the outer tool cylinder having a shoulder, of a piston movable in the inner cylinder, a hollow distributing valve the interior surface of which is open to fluid pressure upon opening the throttle valve, said valve movable in the same direction as the piston but independently thereof, ports controlled by said valve, a pressure chamber at the rear of the inner tool cylinder, a throttle valve for controlling 50 the admission of motive fluid, a passage controlled by said throttle valve through the casing for the motive fluid to exert a pressure against said shoulder, and a stop valve acting in conjunction with said distributing valve, exhaust ports in communication with said pressure chamber and controlled by the throttle valve, a pressure area in said pressure chamber greater than that of said shoulder, said stop valve movable parallel with the distributing valve and controlling ports common to both of said valves, and means whereby said stop valve is positively operated in one direction mechanically and in the opposite direction by fluid pressure.
